APPARATUS FOR LUBRICATION

Halsey G. Kinder, Kenosha, Wis., assignor to
 Macwhyte Company, Kenosha, Wis., a corporation of Illinois

Application September 11, 1937, Serial No. 163,366

8 Claims. (Cl. 184—15)

This invention relates to a method of and an apparatus for applying lubricant to strands of a rope during manufacture. It has for one object to provide means for and a method of lubricating the strands of a wire rope during manufacture so that when finally twisted together the strands are lubricated and carry with themselves and enclose lubricant.

Another object is to provide such a means adapted for the application, while cold, of a lubricant of extremely stiff and viscous qualities, which under ordinary conditions and by ordinary means could not be applied mechanically with convenience. The word "cold" in this connection is to be understood as meaning in general the room temperatures which may prevail in rope making plants. In one sense, such temperatures cannot be considered cold. The word as used means that no particular heating steps have been applied to the lubricant. The invention is of particular importance in connection with the application of lubricant which at this ordinary cold or room temperature does not "flow" and cannot be readily poured or pumped upon the wire strands.

Other objects will appear from time to time in the course of the specification and claims.

The invention is illustrated more or less diagrammatically in the accompanying drawing, wherein:

Figure 1 is a vertical sectional view of one form of the device;

Figure 2 is a plan view with parts in section at line 2—2 of Figure 1; and

Figure 3 is a vertical sectional detail taken on line 3—3 of Figure 1.

Like parts are indicated by like characters throughout the specification and drawing.

The apparatus of the invention as illustrated is designed to feed vertically upward. This is not essential and the device might be arranged to feed laterally, horizontally, or at an angle to the horizontal. Where that is done, an angular drive might be required, but it is within the contemplation of the invention to feed grease or lubricant of the type indicated in any direction in which it is needed.

While the invention is shown as applied to the so-called "horizontal" rope machine, as shown in Figure 3, into which the rope is formed horizontally, it might equally well be applied to a mechanism in which the rope is formed vertically.

In the form shown, 1 is the foundation or base plate of any desired design. Upon this is secured a base member 2 which forms the bottom of the

lubricant container. Portions 3 project downwardly from the base 2 and serve as bearings for the drive shaft 4. At its outer end the drive shaft 4 carries a gear 5 which meshes with the pinion 6 on a shaft 7 of a motor 8. This motor 5 may be supported on the member 1 and serves as a means for driving the shaft 4 and also through it for driving the lubricant feed.

The shaft 4 carries secured to it a pinion 9 which meshes with a gear 10 on a shaft 11 which 10 passes through a suitable perforation in the base member 2 and may also have an antifriction bearing 12, which as here shown, is a thrust bearing.

Secured to the shaft 11 is a member 13 to which 15 are secured a plurality of agitator arms or rods 14, each of which may have its outward end forwardly bent in the direction of its rotation as at 15, as shown in Figure 2. The direction of rotation of the agitator is indicated by the arrow in that figure. Secured to the member 13 is a feed screw 16. This screw is enclosed within a tube 17 which is mounted within and preferably secured to a ring or hub 18 from which a plurality of arms 19 project laterally and join an outer or 25 ring portion 20.

The side walls of the lubricant container are formed by a member 21 which may in effect be a tube, the upper end of which is received against the shoulder 22 in the member 20, the lower edge 30 of which is received against the shoulder 23 in the member 2. Bolts or screws 24 serve to hold the parts in assembled position, but adjustment is possible by loosening the bolts and rotating the ring or tube 21. Secured by welding or otherwise to the upper edge of the tubular portion 21 is a pan 25 which, as shown in Figures 1 and 2, may be enlarged at one side so as to have a projecting portion 26. The one advantage of this projecting portion is that it furnishes a convenient means for replenishing the supply of lubricant within the pan as a whole, the projecting portion extending beyond the rope and beyond adjacent machine parts so that the operator can conveniently place lubricant in the pan.

Slidably and rotatably mounted about the tube 17 is a second tube 27. This tube fits preferably snugly about the tube 17 and may be relatively flattened toward its upper end, as shown in Figures 1 and 3 at 28. It is preferably cut away 50 partially as at 29 to permit the strands 30 which are being formed into a rope 31 to pass through the upper end of the tube and thus to be largely surrounded by the tube. Along one side the tube 27 may be provided with a by-pass slot 32 55

as shown in Figure 3. This slot is preferably of the same diameter as the by-pass hole 33 shown in Figures 1 and 3.

Positioned about the tube 21 and in contact with it is a third tube 34 which may be provided with a handle 35. The tube is also slotted as at 36, as shown in Figure 3.

By means of the handle 35, the tubes 27 and 34 may be raised together, thus adjusting the position of the cut-away portion 29 into the desired height to accommodate it to the particular machine or rope through which it is used. The tube 34 may also be rotated by the handle 35 and in normal position it would be rotated so that the slot 36 is not in line with the opening 33, and thus escape of lubricant from the interior of the tube is prevented. As shown in Figure 3, the slots 32 and 36 are in line with the opening 33 and lubricant could escape. This will ordinarily not be the condition during operation. They are shown in use in Figure 3 for purposes of simplicity and to avoid confusion, although the mechanism is otherwise shown in the condition which it occupies when in operation, that is to say, when feeding lubricant to the strands of the rope during the manufacture.

In Figure 3 the mechanism is shown as in operation except for the position of the slots 32 and 36 as just mentioned. While the invention is not limited to association with any particular rope machine or method, as shown in Figure 3, which will serve for one illustration of the use of the invention, the wire strands 30 are being brought together at approximately the point 37 where they enter a forming die 38. This die may be of any suitable form, its details forming no essential part of the invention. It is carried in a frame member 39 that is preferably or movably held in position by a locking and adjusting screw 40 upon which a thumb nut 41 may be mounted.

The use and operation of the invention are as follows:

Before use, the machine of course is positioned upon or adjacent to a rope making machine and the angle or direction of the feed is adjusted suitably for the particular rope machine. The feed may thus be vertical or horizontal or at any angle. If the feed is horizontal, a slightly modified form for pan or lubricant container would be necessary. After the adjustment of the mechanism of the present invention to the rope machine has been made, the tubes may be raised or lowered to bring the cut-away portion 29 in exactly the proper position with respect to the strands of wire. The drive for the screw 16 is then set in operation and lubricant within the pan and container is forced upwardly by the screw and discharged into the flattened portion 28 of the tube and moves upwardly due to the cut-away portion 29 through which the strands of the wire rope are passing and these strands are thus caused to pass through a constantly rising positively driven column of lubricant, and are thus lubricated as they pass into the rope and lubricant is carried by them and with them into the rope. The portions of the tube which surround the cut-away portions 29 sufficiently retain and compact the lubricant to hold it together so as to produce the proper degree of concentration at the point where lubricant and wires come in contact with each other. The lubricant which is not carried away by the wires spills or falls over and back into the pan 25 or the lower portion of the container 21.

During the normal operation of the device, the agitators 14 rotate with the screw 16 and serve to keep the lubricant in motion and also serve to prevent any collection or unequal distribution of the lubricant within the container. In particular, if the lubricant within the container is fairly reduced in supply, the agitators maintain an equal distribution to maintain constant and equal action of the screw 16 in steadily feeding the lubricant to the point of use.

Sometimes it is desirable to stop the feed of lubricant to the rope for a brief interval and that may be done by moving the outer tube 34 into the position shown in Figure 3 so that the slot 36 is in register with the slot 32 of the tube 21 and both are in register with the opening 33 of the inner tube 17. In that case, the lubricant is by-passed through these openings. For certain purposes, also, where the rope does not take up or require the full capacity of the grease which is fed to it by the screw 16, these by-pass passages may be left open so that a certain amount of the lubricant fed along by the screw is by-passed without being carried the full distance to the cut-away portion 29 and to the wire strands passing through it. While no particular means is shown for holding the tubes in any vertical or rotational position of adjustment, it is obvious that such a mechanism may be used in a variety of details and its use is within the contemplation of the present invention.

I claim:

1. In combination in a lubricant applying apparatus, a container, and means for positively feeding lubricant from said container to a point of use, said means comprising a screw, and a plurality of agitator members, means for rotating said agitators and said screw, and a guide tube positioned about said screw and partially within said container, said screw extending beyond the inner end of said tube directly into said container, and a second tube positioned about said first tube and mounted for axial and rotational adjustment with respect to said first tube, said first tube provided with a laterally faced opening, said second tube provided with a longitudinally aligned slot, the upper end of said second tube extending upwardly beyond said first tube, and being partially cut away to provide a lubricant supplying zone through which work pieces may pass.

2. In combination in a lubricant applying apparatus, a container, and means for positively feeding lubricant from said container to a point of use, said means comprising a screw, and a plurality of agitator members, means for rotating said agitators and said screw, and a guide tube positioned about said screw and partially within said container, said screw extending beyond the inner end of said tube directly into said container, and a second tube positioned about said first tube and mounted for axial and rotational adjustment with respect to said first tube, said first tube provided with a laterally faced opening, said second tube provided with a longitudinally aligned slot, the upper end of said second tube extending upwardly beyond said first tube, and being partially cut away to provide a lubricant supplying zone through which work pieces may pass, and a third tube positioned about said second tube and provided with an axially aligned slot.

3. In combination in a lubricant applying apparatus, a container, and means for positively feeding lubricant from said container to a point

of use, said means comprising a screw, and a plurality of agitator members, means for rotating said agitators and said screw, and a guide tube positioned about said screw partially within and partially outside of said container, said screw extending beyond the inner end of said tube directly into said container said tube being perforated in its side, and a second tube positioned about said first tube and mounted for axial and rotational adjustment with respect to said first tube, the upper end of said second tube extending upwardly beyond said first tube, and being partially cut away to provide a lubricant supplying zone through which work pieces may pass, said second tube being slotted, and a third tube positioned about said second tube said third tube being slotted, and means on said third tube for raising said second and third tubes to effect elongation of the total guide tube.

4. In combination in a lubricant applying apparatus, a container, and means for positively feeding lubricant from said container to a point of use, said means comprising a screw, and a plurality of agitator members, means for rotating said agitators and said screw, and a guide tube positioned about said screw and partially within said container, said screw extending beyond the inner end of said tube directly into said container, and a second tube positioned about said first tube and mounted for axial and rotational adjustment with respect to said first tube, said first tube provided with a laterally faced opening, said second tube provided with a longitudinally aligned slot, the upper end of said second tube extending upwardly beyond said first tube, and being partially cut away to provide a lubricant supplying zone through which work pieces may pass, and a third tube positioned about said second tube and provided with an axially aligned slot, and means on said third tube for raising said second and third tubes and for rotating said third tube with respect to said first tube to bring the slot in said third tube into and out of alignment with the lateral opening in said first tube.

5. In combination in a lubricant applying apparatus, a container, and means for positively feeding lubricant from said container to a point of use, said means comprising a screw extending to a point adjacent the bottom of said container, and a plurality of agitator members mounted in fixed relation with said screw, means for rotating said agitators and said screw in unison, and a laterally perforated guide tube positioned about said screw partially within and partially without said container, said screw extending beyond the inner end of said tube directly into said container, and a second tube positioned about said first tube said second tube being slotted and mounted for axial and rotational adjustment with respect to said first tube, the upper end of said second tube extending upwardly beyond said first tube, and being partially cut away to provide a lubricant supplying zone through which work pieces may pass.

6. In combination in a lubricant applying apparatus, an open-topped container, and means for positively feeding lubricant from said container to a point of use, said means comprising a screw extending to a point adjacent the bottom of said container, and a plurality of agitator members mounted in fixed relation with said

screw, means for rotating said agitators and said screw in unison, the agitators comprising radially positioned rod-like members having their outer ends bent to face in the direction of their rotation, and a laterally perforated guide tube positioned about said screw partially within and partially without said container, said screw extending beyond the inner end of said tube directly into said container, and a second tube positioned about said first tube said second tube being slotted and mounted for axial and rotational adjustment with respect to said first tube, the upper end of said second tube extending upwardly beyond said first tube and beyond said second tube, and being partially cut away to provide a lubricant supplying zone through which work pieces may pass.

7. In combination in a lubricant applying apparatus, a container, and means for positively feeding lubricant from said container to a point of use, said means comprising a screw extending to a point adjacent the bottom of said container, and a plurality of agitator members, means for rotating said agitators and said screw, the agitators comprising radially positioned rod-like members, and a guide tube positioned about said screw and partially within said container, said screw extending beyond the inner end of said tube directly into said container, and a second tube positioned about said first tube and mounted for axial and rotational adjustment with respect to said first tube, said first tube provided with a laterally faced opening, said second tube provided with a longitudinally aligned slot, the upper end of said second tube extending upwardly beyond said first tube, and being partially cut away to provide a lubricant supplying zone through which work pieces may pass, and a third tube positioned about said second tube and provided with an axially aligned slot.

8. In combination in a lubricant applying apparatus, an open-topped container, and means for positively feeding lubricant from said container to a point of use, said means comprising a screw extending to a point adjacent the bottom of said container, and a plurality of agitator members mounted in fixed relation with said screw, means for rotating said agitators and said screw in unison, the agitators comprising radially positioned rod-like members having their outer ends bent to face in the direction of their rotation, and a guide tube positioned about said screw and partially within said container, said screw extending beyond the inner end of said tube directly into said container, and a second tube positioned about said first tube and mounted for axial and rotational adjustment with respect to said first tube, said first tube provided with a laterally faced opening, said second tube provided with a longitudinally aligned slot, the upper end of said second tube extending upwardly beyond said first tube, and being partially cut away to provide a lubricant supplying zone through which work pieces may pass, and a third tube positioned about said second tube and provided with an axially aligned slot, and means on said third tube for raising said second and third tubes and for rotating said third tube with respect to said first tube to bring the slot in said third tube into and out of alignment with the lateral opening in said first tube.

HALSEY G. KINDER.
